(57) **CLAIM**

The ornamental design for a ceiling fan with light as shown and described.

DESCRIPTION

FIG. 1 is a perspective view of a ceiling fan with light showing my new design;

FIG. 2 is another perspective view thereof;

FIG. 3 is a front view thereof;

FIG. 4 is a back view thereof;

FIG. 5 is a left and right view thereof;

FIG. 6 is a top plan view thereof;

FIG. 7 is a bottom plan view thereof;

FIG. 8 is a perspective view shown in another state;

FIG. 9 is a front view shown in another state; and,

FIG. 10 is a partial enlarged view of portion 10 in FIG. 1. The broken lines depict portions of the ceiling fan with light and form no part of the claimed design.

The dot dash line is included for the purpose of illustrating the bounds of the enlarged view and forms no part of the claimed design.
